UNITED STATES PATENT OFFICE.

ALBERT D. GROVER, OF MALDEN, MASSACHUSETTS.

BRIDGE FOR MUSICAL INSTRUMENTS.

SPECIFICATION forming part of Letters Patent No. 769,649, dated September 6, 1904.

Application filed April 29, 1904. Serial No. 205,620. (No model.)

To all whom it may concern:

Be it known that I, ALBERT D. GROVER, a citizen of the United States, residing at Malden, county of Middlesex, and State of Massachusetts, have invented certain new and useful Improvements in Bridges for Musical Instruments, of which the following is a specification, taken in connection with the accompanying drawings.

10 The object of my invention is to so construct a bridge for musical instruments that it will be supported laterally and prevented from tipping over sidewise from vibration of the strings or otherwise.

15 Another object of my invention is to provide one or more adjustable transverse supports to a bridge provided with feet adapted to contact with the top of the body part of the instrument and adapted to be moved longitudinally to a point under any particular string to support the bridge laterally and to increase the volume of tone of the string under which the support is placed.

20 Referring to the drawings accompanying and forming a part of this specification, in which similar letters refer to similar parts throughout the several views, Figure 1 represents a perspective view of a bridge having an adjustable lateral support. Fig. 2 represents a sectional end elevation on line 22, Fig. 1. Fig. 3 is a bottom plan view of said bridge.

25 In the drawings, A represents the body part of the bridge, and A' A' the downward-extending feet thereof, which contact with the top of the musical instrument. As will be noted, the form of the body part A is wedge shape, with the point cut off, the body being narrower at the top than at the bottom.

30 B is a transverse support which is provided with the feet B' B' and a dovetail notch B' in its upper portion adapted to fit the downwardly-diverging walls of the wedge portion of the body part A. The wedge-shape feature is more clearly shown in the end elevation, Fig. 2.

35 C C C represent a non-slipping material inserted in the feet of the bridge and the transverse support, which non-slipping material may be composed of rosin melted to form 40 the shape indicated, or it may be formed of

glue having a rougher non-slipping substance, such as fine emery-dust or fine sandpaper-dust, mixed therewith. The object of this non-slippable material is to present a rough surface that will cling to the top or body part of 55 the musical instrument.

As illustrated in Figs. 1 and 2, the transverse support B may be moved from one end of the bridge to the other, as the wedge-shape portion of the body part A of the bridge is of 60 uniform thickness from end to end. The body portion of the bridge is provided with the notch A' in order that the support can be disconnected for packing.

65 The bridge shown in the drawings is provided with the transverse slots or notches K K K K, adapted to receive the strings of the instrument; but I do not confine myself to five notches, as the number of notches is immaterial to the operation of my bridge and may 70 be varied to suit the particular instrument with which my improved bridge is used.

75 My invention may be embodied in other forms of bridges, the form alone being immaterial, as the essential features of the invention consist in providing a lateral support for a bridge, as well as making the support adjustable as desired, so that the support may be moved to a position under any particular string when it is desired to increase the volume of its tone.

80 It being well known that the tone of the instrument is brought out through the vibrations of strings attached thereto under tension and bearing upon a bridge the feet of 85 which are pressed upon the top of a hollow body adapted to accent or increase the volume of the tone due to the vibrations of the strings, by increasing the contact-surface of the bridge within proper limits the volume of tone given 90 forth by the string is increased.

Having described my invention, what I claim is—

1. A bridge for stringed musical instruments, provided with a lateral support attached to its body part and adjustable thereon. 95

2. A bridge for stringed musical instruments, provided with one or more adjustable lateral supports attached to its body part.

3. A bridge for stringed musical instru- 100

ments having a body part provided with downwardly-diverging wedge-shaped walls; a lateral support for said bridge provided with an opening adapted to fit the wedge-shaped walls of the bridge and be secured thereto.

4. A bridge for musical instruments composed of a wedge-shaped body part; a lateral support having a wedge-shaped opening to fit said body part; and notches in the body part to permit the connecting and disconnecting of the lateral support.

5. A bridge for stringed musical instruments, provided with a lateral support attached to its body part and adjustable thereon, the feet of said bridge having recesses therein filled with rosin or rosin composition, to prevent slipping.

6. A bridge for stringed musical instru-

ments, provided with one or more adjustable lateral supports attached to its body part, the bridge having feet; recesses in said feet, said recesses being filled with rosin or rosin composition to prevent slipping.

7. A bridge for stringed musical instruments, provided with one or more adjustable lateral supports attached to its body part, the feet to said bridge and supports having attached to the surface thereof a non-slipping material.

In testimony whereof I have hereunto set my hand, in the presence of two subscribing witnesses, this the 25th day of March, A. D. 1904.

ALBERT D. GROVER.
